UNITED STATES PATENT OFFICE.

HENRY J. LOTZ, OF MCKENNA, WASHINGTON.

BLOCK-LETTER HOLDER.

Application filed August 3, 1927. Serial No. 210,246.

This invention relates to devices for holding blocks in alignment and has special reference to such devices for holding letter blocks therein. The objects of the invention are, first, to provide a means whereby any block or series of blocks may be held firmly therein; second, whereby any blocks may be quickly and easily removed therefrom; third, whereby such blocks are clamped 10 therein to form therewith a single structure which may be handled as a unit for any desired purpose. Another object is to provide such a device as will be practically indestructible in ordinary use; which is of light 15 weight; and which is cheap to make, simple to operate, and which effectively holds the blocks in place.

I attain these and other objects by the devices, mechanisms, and arrangements illustrated in the accompanying drawings, in which—

Fig. 1 is a plan view showing my device ready for use as a holder for block type adapted for use in impressing letters in 25 green concrete, or artificial stone; Fig. 2 is a side elevation thereof; Fig. 3 is a perspective view of one of the letter blocks; Fig. 4 is an end view, partly in section, of the main holder; Fig. 5 is an end view of the 30 clamping bar; and Fig. 6 is an end elevation of the complete device, ready for use.

Similar numerals of reference refer to similar parts throughout the several views.

My invention is capable of being used in a large variety of arts, for instance, it may be used for impressing names, or other words, in concrete, while in a green or soft condition, as, for instance, the names of persons or of streets, or the numbers of houses, in sidewalks; or for impressing words in brick, tile, or other clay products, while in a plastic condition; or the names of a person, and other data, in the lid of a concrete 40 burial box or sarcophagus; or for printing block letters for signs and posters; or it may be secured to a post and the letters therein indicate the street, road, or other public direction or notice. It may be adapted either for hand use, as shown, or it may be attached to suitable machinery whereby it is 45 moved and actuated.

Referring, now, to the drawings, in which I have illustrated a form of my invention adapted for hand use and for impressing

the block letters mounted thereon in green 55 concrete, or other plastic or semiplastic material, it will be seen that the main holder is preferably made of bent sheet metal and comprises a long body of general rectangular section (Fig. 4) having a base 1, two 60 sides 2, which are bent inward along their upper edge to form the two guide rails 3. The two said guide rails 3 lie in the same plane and are separated by a space, as clearly shown in the drawings. 65

The clamping bar (Fig. 5) comprises a similarly shaped bent sheet metal strip, adapted to be placed within the main holder and formed with a base 4, of slightly less width than the base 1; two sides 5, of considerably less depth than the sides 2; and two guide rails 6, which are separated by a space substantially equal to the space between the guide rails 3 of the main holder. The clamping bar, thus formed, is adapted 70 to lie within the main bar or holder with its guide rails 6 immediately below the guide rails 3 thereof.

The main holder and the clamping bar cooperate to clamp the block letters, and for 80 this purpose may be adjustably secured together in any suitable manner, it being understood that it is desired to forcibly separate the guide rails 6 of the clamping bar from the corresponding guide rails 3 of the main holder. In the drawings, I have shown a plurality of screws 7, rotatably secured in the base 4 of the clamping bar, by means of heads 8. These screws 7 may be provided with wing heads 9 whereby they may be turned. The screws 7 are threaded through nuts 10, secured in the base 1 of the main holder. In assembling this device, the clamping bar is inserted within the main holder and then the screws are inserted through the nuts 10, and through the base 4 of the clamping bar, and are riveted or otherwise secured thereto in such manner as to be free to rotate therein. Thus by turning the screws 7 in a counter-clockwise 90 direction the clamping bar is drawn downward by the riveted heads 8, on the inner side of the base 4, and the guide rails 6 are 95 separated from the guide rails 3, as desired.

It is to be understood that other suitable 105 means may be employed to separate the said guide rails, for instance, the screws may be secured to the base 4 of the clamping bar

and may pass freely through holes in the base 1 of the main holder and may be provided with nuts, winged or otherwise, screwing thereon and pressing against the under 5 surface of the base 1, thereby drawing the screws downward and separating the guide rails 3 and 6, as desired.

The letter blocks 11 are formed with grooves 12 in their alined sides, said grooves 10 being deep enough to receive the guide rails 3 and 6, the width of said blocks being less than the width of the base 4 of the clamping bar (Fig. 6). Letters 13, figures, or other signs, may be formed on or secured to the 15 top side of the block 11 and may be in relief or in intaglio.

The ends 14 of the main holder may preferably extend out beyond the main body thereof to form a handling means or a means 20 to which the operating mechanism may be attached when the device is used in a machine.

My device is used in the following manner:—

25 The screws 7 are all turned to push the guide rail 6 close to the guide rail 3, then the several blocks are slid into proper place therein, in order, the said guide rails 3 and 6 entering the said grooves 12 therein. Then 30 each of the said screws 7 are turned to draw the clamp bar base 4 towards the base 1 of the holder thus forcing the guide rails 6 to pull down on the lower surface of the groove 12 and clamping each of the said blocks 11 35 in its place.

Having, therefore, described my invention, what I claim is:—

1. A device of the class described, comprising a U-shaped holder having inward-extending guide rails on its opposite sides; a 40 U-shaped clamping bar, lying in said holder and having similar inward-extending guide rails on its opposite sides; a block having grooves in its opposite sides and adapted to lie in said clamping bar and to engage both 45 guide rails of the holder and of the clamping bar; and means forcing the clamping bar down in the holder to separate its guide rails from those of the holder and to clamp the block by said guide rails engaging the 50 upper and lower sides of said grooves respectively.

2. A device of the class described, comprising a U-shaped holder having inward-extending guide rails on its opposite sides; a 55 U-shaped clamping bar, lying in said holder and having similar inward-extending guide rails on its opposite sides; a block having grooves in its opposite sides and adapted to lie in said clamping bar and to engage both 60 guide rails of the holder and of the clamping bar; and screw means, engaging the holder and the clamping bar and adapted to force the clamping bar down in the holder to separate its guide rails from those of the 65 holder, and to clamp the block by said guide rails engaging the upper and lower sides of said grooves, respectively.

HENRY J. LOTZ.
